UNITED STATES PATENT OFFICE.

JUNIUS A. McCORMICK, OF PITTSBURG, PENNSYLVANIA.

MAN AND HAND HOLE CONNECTION FOR BOILERS.

No. 853,821.

Specification of Letters Patent.

Patented May 14, 1907.

Application filed November 3, 1906. Serial No. 341,937.

To all whom it may concern:

Be it known that I, JUNIUS A. McCORMICK, a resident of Pittsburg, in the county of Allegheny and State of Pennsylvania, have invented a new and useful Improvement in Man and Hand Hole Connections for Boilers; and I do hereby declare the following to be a full, clear, and exact description thereof.

My invention relates to a device for closing handholes or manholes in boilers, and its object is to provide means for this purpose which will prevent leakage when the pressure in the boiler drops.

The usual means employed for closing handholes and manholes comprises a plate seated against the inner face of the boiler head or body and having connected thereto a bolt which extends out through a yoke or arch piece seated against the outer face of the boiler head or body and a nut screws onto the outer end of the bolt and bears against the yoke or arch piece, and draws the plate to a steam tight joint against a rubber, lead or other gasket on the inner face of the boiler head or body. When the boiler is in use the pressure of the steam therein forces the handhole plate against the gasket, thus compressing the latter and producing a certain amount of slack between the nut and the yoke. When the pressure drops this slack permits the plate to move away from the gasket and as the latter becomes permanently compressed and loses its elasticity, leakage occurs. To prevent this it has been found necessary to tighten the nuts up before the boiler cools down so as to take up the slack between the nut and yoke caused by the compression of the gasket. This necessitates much additional labor on the part of the engineer and is often neglected and if it is not carefully watched the leakage gives trouble.

The present invention is intended to overcome the above difficulty and to do away with the necessity of tightening up the nuts on the handhole bolts as above described.

It consists, generally stated, in combination with the boiler having a manhole or handhole, a plate closing the same and seated against the inner face of the boiler, and spring controlled means for holding the plate to its seat, such as by the interposition of a spring between the yoke or arch piece and the nut engaging the bolt.

In the accompanying drawings, Figure 1 is a sectional view illustrating the end of a

water tube boiler employing the invention; Fig. 2 is a perspective of part of the boiler head; Fig. 3 is a section through the handhole and plate; Fig. 4 is a view illustrating the invention applied to the manhole at the end of an ordinary boiler, or like drum.

The boiler to which the invention may be applied may be of any construction, that shown in the drawing being simply illustrative. In the illustration of the tubular or water tube boiler, the boiler head is shown at 1 having the handhole openings 2 with which the ordinary handhole plates 3 engage, these plates being inserted through the handholes which are out of true circular shape and so permit their insertion as is usual in such construction. The handhole plate 3 has the flange 4 which engages with the ordinary rubber, lead or other gasket 5 seated on the inner face of the boiler head. The plate 3 has the bolt 6 secured thereto in any suitable way which extends outwardly through the yoke or arch piece, the outer end of same being threaded to receive the nut 8. Interposed between the nut 8 and the arch piece 7 is a strong spring 9. Any suitable spring may be employed for this purpose, that which I have illustrated being a spiral spring. The device so shown is illustrative of the general principle of the invention which includes any spring controlled means for holding and seating the handhole plate against the inner face of the boiler head or wall. The interposed spiral spring for this purpose is believed to be as simple and effective a device as is known.

The spring is of sufficient strength to hold the handhole plate 3 to its seat and take up any slack which might occur by reason of the compression of the gasket 5. When the handhole plate is applied the nut 8 is screwed down firmly, thus putting the spring 9 under compression. Consequently, when the pressure in the boiler forces the handhole plate 3 tightly against the gasket 5 and the latter becomes compressed, the spring 9 expands and thus automatically takes up any slack between the nut and the yoke due to this cause. Consequently, when the boiler cools down and the pressure drops, this spring holds the plate tightly against the gasket, thus acting automatically to provide a steam tight joint between the plate 3 and the gasket 5 at all times and overcoming any tendency to leak and also dispensing with the necessity of tightening up the nuts as heretofore.

The invention as illustrated in Fig. 4 is the same in principle, being simply applied to the manhole in an ordinary boiler or like drum. In said figure the drum head 12 has the inturned flange 13 and the manhole plate 14 has a flange 15 fitting against the inturned flange of the drum head; and the gasket 16 is confined between the manhole plate and said flange. The bolt 17 engages the manhole plate and passes through the yoke or arch piece 18 and through the spring 19 and is secured by the nut 20. The same advantages are realized in this construction as that described in connection with the hand-
15 hole plate illustrated in the other figures.

What I claim is:

1. In combination with a boiler or drum having a manhole or handhole, a plate seated against the inner face of the boiler or drum body, and spring controlled means for holding the plate to its seat.
2. In combination with a boiler or drum having a manhole or handhole, a plate closing or seated against the inner face of the boiler or drum body, a yoke or arch piece engaging the outer face of the boiler body, a bolt connected to the plate and extending through the arch piece, and a compression spring confined between the yoke and the nut holding the bolt.
3. In combination with a boiler or drum having a manhole or handhole, a plate clos-

ing or seated against the inner face of the boiler body, a yoke or arch piece engaging the outer face of the boiler or drum body, a bolt connected to the plate and extending through the arch piece, and a spiral spring surrounding the bolt and confined between the yoke and the nut securing it in place.

4. The combination with a rigid manhole or handhole plate, and a rigid arch or yoke of spring controlled means for drawing the manhole plate toward the arch.

5. The combination with an inelastic manhole or handhole plate having a compressible gasket arranged at the edge of the plate, of a rigid arch, a bolt passing through the arch and movable therein, said bolt being connected to said plate, a nut carried by said bolt and a spring interposed between the said nut and the said arch.

6. In combination with a boiler or drum having a manhole or handhole, a plate seated against the inner face of the boiler or drum body, and spring controlled means for holding the plate to its seat, constructed and adapted to operate independently of the elasticity of the handhole plate.

In testimony whereof, I the said JUNIUS A. McCORMICK have hereunto set my hand. 60
JUNIUS A. McCORMICK.
